UNITED STATES PATENT OFFICE

CARL HUGO JACOBSON, OF BRIDGEPORT, CONNECTICUT

DESIGN FOR A COMBINED WEIGHING SCALE COLUMN AND TARE BEAM BOX

Application filed September 2, 1932. Serial No. 44,738. Term of patent 14 years.

To all whom it may concern:

Be it known that I, CARL HUGO JACOBSON, a citizen of Sweden, residing at Bridgeport, county of Fairfield, and State of Connecticut, have invented a new, original, and ornamental Design for a Combined Weighing Scale Column and Tare Beam Box, of which the following description, in connection with the accompanying drawing, is a specification.

Fig. 1 is a front elevation; and

Fig. 2 is a side elevation of a combined weighing scale column and tare beam box, showing my new design.

I claim:

The ornamental design for a combined weighing scale column and tare beam box, substantially as shown.

CARL HUGO JACOBSON.
